UNITED STATES PATENT OFFICE.

THOMAS W. BRACHER, OF NEW YORK, N. Y.

HAT.

SPECIFICATION forming part of Letters Patent No. 354,882, dated December 28, 1886.

Application filed January 14, 1886. Serial No. 188,547. (No model.)

To all whom it may concern:

Be it known that I, THOMAS W. BRACHER, of the city, county, and State of New York, have invented an Improvement in Hats, of which the following is a complete specification, reference being had to the accompanying drawings, in which—

Figure 1 is a side view of a hat having my invention. Fig. 2 is a detailed top view of the curl of such hat. Figs. 3, 4, and 5 are cross-sections through different forms of hats having my invention. Figs. 6 and 7 are face views of blanks for the clasps which are employed. Figs. 8 and 9 are enlarged cross-sections of the curl or binding-strip and clasp of the hat, to which hereinafter further reference will be made.

The object of this invention is to increase the durability of the curl or edge of a hat, to produce more uniform results in regard to shape, improve the contour, lessen the cost, and to make the curl or edge stronger and stiffer than the rest of the hat.

Hats as heretofore made, speaking more particularly of the semi-stiff felt hats, are either constructed with the crown, brim, and curl in one piece, which is an expensive procedure and leaves the curl as flexible as the balance of the hat, or the curls have been made of separate material, as, for instance, in Patent No. 160,091.

My invention consists, principally, in supplying the curl or edge of a hat, no matter of what material the same be made, with a circumferential compressed binding-spring, by means of which the flexible curl or edge is rendered stiff and durable.

It also consists in a particular construction of curl which is combined on its inner edge with the above-mentioned or a suitable circumferential spring, all as hereinafter more fully described.

In the drawings, the letter A represents a felt hat, or one made of any other suitable material. a is its brim, and b its curl, which is usually turned inward on the brim. The inner edge of this curl is clasped by a metallic spring, B, which is U-shaped in cross-section, as in Fig. 4 of the drawings. This circumferential

spring, when properly attached to the edge of 50 the brim or curl, will embrace the same, being compressed thereon so as to stiffen the same, and will thereby permit the remaining parts of the hat to be made of lighter material than if this stiff spring were only placed in a tubular pocket, as heretofore.

Fig. 3 shows the stiff spring B applied to the edge of the brim of a hat which has no special curl. Where the U-shaped spring is used, (I mean that represented in Fig. 4,) its 60 ends, where they meet, are by preference secured to the curl by a clasp, C. This clasp is made of a blank of the form shown in Fig. 6, or that shown in Fig. 7, and is bent into U-shaped cross-section, the serrated or flat edge 65 being turned or pressed into the body of the brim or curl, as in Fig. 9. By means of this clasp C the spring will be firmly held in position. At any rate, it is my intention to secure the spring B to the hat so that it shall be im- 70 movable thereon. The employment of this stiff spring B enables me to utilize for the brims of the felt hats of the kind shown in Fig. 1 the "roundings"—that is, the waste oval rings which result from the trimming of hat-bodies, and which at present are thrown away, because if they were stitched as curls to a hat they would be without sufficient body or 75 resisting power to permit their employment. When, however, such oval ring d of felt, (see 80 Fig. 2 of the drawings,) which otherwise would be waste, is bound on the inner edge with the compressed metallic spring B, or with a flat spring incorporated into its edge, as in Fig. 5, it receives the necessary rigidity to permit its 85 use on the hat, in which case the outer edge of this ring d, after having been trimmed to correspond with the edge of the brim, is stitched to the latter or fastened thereto in any other suitable manner.

The spring shown in Fig. 5 can be fastened by stitches or clasps.

I do not claim putting U-shaped or other springs into tubular pockets, as in Patent No. 74,392.

I claim—

1. The hat having the periphery and a margin of each face of its brim covered with a con-

tinuous circumferential spring, B, which constitutes a binding and a stiffener for the brim, as specified.

2. The combination of a hat with a detached curl of fabric which has its inner edge provided with a circumferential spring, as described.

3. As a new article of manufacture, a de-

tached hat-curl of fabric combined with the circumferential spring on the inner edge, as described.

THOMAS W. BRACHER.
